RADIO WAVE GUIDE

William E. Bradley, Swarthmore, Pa., assignor, by
mesne assignments, to Philco Corporation,
Philadelphia, Pa., a corporation of Pennsylvania

Original application August 15, 1944, Serial No.
549,618. Divided and this application August
31, 1944, Serial No. 552,174

11 Claims. (Cl. 178—44)

1

This application is a division of my application Serial No. 549,618, filed August 15, 1944, now abandoned, and relates in general to the fields of ultra-high frequency signal transmission and more particularly concerns novel means for generating particular modes of wave transmission.

In micro-wave transmission in wave guides and in various other applications, it is often desirable to transmit a single oscillation mode. For example, for transmission over a considerable distance, it is well known that the TE₀₁ mode of propagation is that which involves the lowest attenuation loss.

Moreover, for certain directional antenna structures, it is desirable to drive with a particular oscillation mode in order to obtain the required directional characteristic, as for example a horizontally polarized energy distribution pattern omnidirectional in the horizontal plane. An antenna array comprising a plurality of stacked biconical horns upon a slotted cavity resonator gives an excellent horizontal polarization characteristic of high directivity. The antenna structure is simpler and has lower loss than the conventional stacked di-pole array and is better adapted to operation on ultra high frequencies. It therefore has considerable application in micro-wave transmission.

However, in order to obtain a uniform circular energy distribution from the stacked biconical horn antenna, it has been found that excitation must be accomplished by the TE₀₁ mode of oscillation. Should other modes enter the driving cavity towards this positive antenna, the field distribution pattern at a distance from the antenna will no longer be quite circular, but will have pronounced symmetrical lobes, the number of which will be determined by the nature of the spurious oscillation modes. For example, it has been found that attempts to excite a TE₀₁ oscillation mode have been accompanied by the generation of a considerable TE₂₁ mode in a circular pipe.

Since the TE₂₁ oscillation can exist in a smaller diameter pipe than the TE₀₁, it is ordinarily difficult to remove this spurious mode. In the stacked biconical horn antenna structure, the TE₂₁ wave will result in a pronounced four-way symmetry over the circular horizontal field distribution obtained by the TE₀₁ wave alone.

In the past, attempts to generate the low attenuation TE₀₁ oscillation mode have been accomplished by complex driving apparatus and have resulted in an impure wave, including several other oscillation modes. It has thus become the

2

practice to attempt to resonate the antenna structure whenever possible for the TE₀₁ wave in order that maximum power output at this mode could be obtained.

5 My invention contemplates a wave guide transmission system including a number of transducers permitting the excitation in one central cavity of the TE₀₁ wave in its pure state.

In order to excite the TE₀₁ mode in a circular wave guide, my invention contemplates the use of a driving network which couples into the circular wave guide through symmetrically arranged slots, excited to an equal extent in the same time phase with respect to the circular wave of the TE₀₁ mode and in the same sense. Feeding energy into the wave guide through a slot prevents any longitudinal field and thus prevents coupling to modes having longitudinal patterns.

In carrying out my invention, coupling into the circular wave guide is effected through two diametrically opposed slots excited equally and in such phase as to excite the TE₀₁ mode. In this arrangement, the TE₂₁ mode is also excited and accordingly provision is made to balance out the TE₂₁ mode.

It is therefore an object of my invention to provide means for generating the TE₀₁ wave in its pure state.

Another object of my invention is to provide transducers for coupling an oscillating source to a wave guide or the like which will transmit only the TE₀₁ oscillation mode.

A further object of my invention is to provide a means for coupling a rectangular wave guide to a hollow circular wave guide in such a manner that the transmitted wave excited in the guide is essentially the TE₀₁ mode.

Another object of my invention is to generate the TE₀₁ oscillation mode in pure form in a circular wave guide.

Still another object of my invention is to utilize a novel arrangement of symmetrical slits in an end plate of a wave guide resulting in the generation of a TE₀₁ wave.

These and other objects of my invention will now become apparent from the following specification taken in connection with the accompanying drawings in which:

50 Figure 1 is a general diagrammatic representation of a stack biconical horn antenna structure coupled to a wave guide in which the TE₀₁ wave is excited.

Figure 2 is a front view of one system for exciting a TE₀₁ wave in a circular wave guide.

Figure 3 is a top view of the wave guide structure illustrated in Figure 2.

Figure 4 is a perspective view of the wave guide structure illustrated in Figures 2 and 3.

Figure 5 is a perspective of a wave guide showing the TE₁₁ mode.

Figure 6 is an end view showing the transverse mode TE₁₁.

Figure 7 is a perspective of a wave guide with a TM₀₁ mode.

Figure 8 is a longitudinal section of Figure 7.

Figure 9 is a cross-section of a wave guide showing the TE₂₁ mode.

Figure 10 is an elongated section of Figure 9.

Figure 11 is a cross-section of a wave guide showing a TE₀₁ mode.

Figure 12 is an illustration of the field distribution at slits in a plate.

In Figure 1, there is illustrated an antenna structure which presents certain decided advantages when driven by a TE₀₁ signal. This antenna structure comprising essentially a stacked biconical horn array is commonly utilized to develop a field distribution having a uniform circular horizontal pattern. That is to say, the signal strength radiated from the structure illustrated in Figure 1 when excited by the TE₀₁ wave is independent of azimuth.

Basically, the antenna structure consists of a segmental cavity resonator 21. This cavity resonator comprises essentially a length of wave guide which is closed at the lower end by an adjustable metallic plate 53, and at the upper end by a movable piston-type plate 23. The movable closure 23 is utilized to resonate the cavity 21 at the desired frequency.

Extending from the outer wall of the cavity resonator 21 are a plurality of plates 24, alternate ones being inverted, and in contact with each other as illustrated by the plates 25 and 26. The cavity resonator 21 is excited as illustrated by energy fed over a hollow wave guide 112. The hollow wave guide 112 is, as will be more fully explained hereinafter, excited by the TE₀₁ mode only.

The coupling from the cavity for the biconical horns illustrated in Figure 1 is obtained by circumferentially slitting the cavity 21 as at 31. The circular slits extend about the entire perimeter of the cavity between the stacked metallic plates as 25 and 23. The supporting means for maintaining the cavity segments such as 21 in the proper spaced relation are not illustrated but of course comprise conventional high frequency insulating means.

By the use of the single resonant cavity illustrated, it is possible by proper placement of the circumferential slits 31 to obtain a highly intense field pattern in the horizontal plane.

The biconical stacked horn arrangement illustrated in Figure 1 is illustrative of an ultra-high frequency system which is best operative from a source of TE₀₁ electro-magnetic waves. Thus, with the use of TE₀₁ waves in the cavity illustrated, the electric field is horizontal at all points and circular about the axis of the cavity. Accordingly, the field pattern radiated through the slits 31 and between the flared horn structure is essentially an intense horizontally polarized signal and has omnidirectional vertical activity. The circumferential slits such as 31 are placed in a location where the waves radiating therefrom are in phase and form as intense a beam as is possible on the horizon. In the illustrated construction, the slits are shown of uniform width,

although this need not always be the case. For example, in the three element structure shown, in order to further suppress side lobes, I prefer to make the center gap approximately fifteen per cent wider than the outer gaps, the latter being kept uniform.

This antenna structure which has lower loss and has far greater utility due to its simplicity than the stacked dipole array is dependent for proper operation upon the excitation of the TE₀₁ waves in pure form in the cavity 21. In the following description, various means will be illustrated embodying my invention for generating a TE₀₁ wave. It is to be understood that the application of the transducers to be described is not necessarily limited to the biconical horn antenna disclosed in Figure 1, but may be utilized wherever transmission of micro-wave for a considerable distance is required.

In order to more fully explain the operation of my novel transducers, a brief review of modes and structures for launching them will be given.

In Figures 5 to 8, I show cavity modes in the order of their appearances as the frequency is raised. When the pipe is large enough to contain several modes, the modes which actually exist depend on the type of launcher.

The first mode that will appear is the TE₁₁, shown in Figure 5. As shown, the TE₁₁ is a transverse mode, the electric fields running from the top to the bottom of the pipe. Between points where there are large electric fields, there are nodal planes where the electric field vanishes. In the case of a traveling wave in the guide, this whole pattern is rushing along the guide and the pattern seems to move faster than the speed of light. In a cavity the pattern stands still, the electric field just reversing its phase at radio frequency. That is the first mode that appears.

This mode obviously has polarization.

It will appear with a polarization determined by the launcher and must be received in a suitable manner. A dipole would do for the launcher and receiver.

The next is a TM₀ mode shown in Figure 6. This mode shows no polarization. The electric field is shown by the arrows. It is conveniently excited by a launcher consisting of a simple quarter-wave antenna standing in the center along the axis.

The TE₂₁ shown in Figure 7 is the next mode. Like the TE₁₁ it is purely transverse, there being no longitudinal electric lines.

Figure 8 is the TE₀₁. There are any number of them beyond these modes, but these will suffice for the present discussion. In the TE₀₁ mode, the electrical field nowhere touches a metal surface.

The TE₀₁ is obviously suitable for the radiation of horizontal polarization through a circumferential slot as shown in Figure 1.

I have discovered that such a mode can be launched by opening a wave guide into a cavity through a symmetrical arrangement of slots.

If, for example, two opposed slots are provided in the bottom of a wave guide fed from a suitable wave guide, it is possible to drive the two slots exactly out of phase and the TE₀₁ mode whose electric field crosses both slots in the same sense is coupled into the wave guide. The TE₁₁ will not be excited since the TE₁₁ has a diametrical electric field across it. It will not couple to TM₀₁ because no net longitudinal electric field is set up.

With an orientation as shown by the two slots in solid lines in Figure 9, the TE₂₁, however, will

5

also be excited. In this figure, the TE_{21} is shown dotted in the form in which it will be coupled. In the neighborhood of the slots, there will be electric fields which will be parallel to the electric field of the slots and the phase will be such as to be excited by two slots which are driven with the sense of field shown by the solid arrows.

Figures 2 to 4 are illustrative of a simple conveniently constructed transducer embodying the above principles in which slots are excited symmetrically and symmetrical branches of wave guides are provided for generating the TE_{01} transmission mode in a circular wave guide. This is called a gallery or two-way drive associated with a critical length to balance out the TE_{21} mode.

As illustrated, a circular hollow wave guide 41 is coupled near one end thereof to a transducer 42 comprising essentially a rectangular wave guide extending from the source of high frequency energy. The hollow wave guide 41 may be coupled to whatever system is being driven by the ultra-high frequency energy, such as the cavity of the biconical horns of Figure 1.

At junction point 43, the rectangular wave guide 42 is split to form a T joint thereat. The two sections of wave guide extending from the joint 43 are circularly bent as best illustrated in Figure 3 to straddle the circular wave guide 41 and form curved sections 44 and 45. The cross-section of the curved sections 44 and 45 is of course rectangular similar to the main guide 42.

The two circular extensions 44 and 45 of the rectangular wave guide 42 are plugged at 46 and 47, Figure 3, respectively, by rectangular plates. At diametrically opposed points 51 and 52, the cylindrical wave guide 41 and the wave guide extensions 44 and 45 are slotted as is best illustrated in Figure 2. These slots 51 and 52 are the electro-magnetic coupling openings between the rectangular guide 42 and the circular guide 41.

As is illustrated in Figure 3, the distance measured along the circumference between the rectangular slot 52 and the metallic plug 47 is substantially equal to one-half the wave length in guide 45. This condition is also true for the distance between the slot 51 and the metal plug 46.

By adjustment of the position of the plug with respect to the slot, the inductance due to the peculiar place of the slit in the guide is compensated out. When the location of these two little plugs are found, they are soldered in place. The cross-sectional dimensions of these branch guides must be carefully chosen by determining what the input impedance of these two slots will be for the TE_{01} mode.

It will now be apparent from the above that the slots will have an induction field having the proper polarization or sense of phase which will tend to drive the TE_{01} . In other words, the slots will be excited in push-pull provided the lengths of the branch guides 44 and 45 are equal.

This gallery type of drive will, however, also excite the TE_{21} as already explained in connection with Figure 9, although it will successfully avoid excitation of TE_{11} and TM_{01} . To balance out the TE_{21} it is effectively short-circuited. This is effected by sealing one end of the circular wave guide 41 by an adjustable circular metal plate 53 as shown in Figure 4. By appropriately determining the length between the rectangular slots 51 and 52 and the metal plate 53, the TE_{21} mode of oscillation may be completely suppressed within the circular wave guide 41. That is to say, by properly choosing the aforementioned dis-

6

tance, the energy of this undesired TE_{21} oscillation mode which enters from the rectangular guide 42 may be completely balanced out. This distance is somewhat critical and is an integral number of half wave lengths of the TE_{21} mode, as measured from the effective center of slots 51 and 52.

The drive mechanism illustrated is such as to permit only the desired TE_{01} oscillation mode to exist within the circular wave guide 41. As is well known, this particular mode will be transmitted down the guide with minimum attenuation. For the particular transducer illustrated in Figures 2 to 4, the two-way symmetry provided by the rectangular slots 51 and 52 permit the transmission of the TE_{01} wave and the metal plate 53 results in the balancing out of undesired oscillation modes.

The principle of operation of the transducer illustrated in Figures 2 and 3 may be summarized by the general statement that the circular wave guide is energized from a transducer comprising two diametrically opposite slots having two-way symmetry in the circumferential or angular dimension. The TE_{01} and TE_{21} are, as will now be clear, produced. The TE_{21} mode is suppressed by sealing one end of the guide at a critical distance from the slots.

To excite the TE_{01} mode, there must be produced at each slot an equal component of electromotive force in the same phase and in a circumferential direction. The length of the guide from the point of junction to the slots must be such that both slots are driven equally. This may be done by the gallery arrangement here illustrated or in any other construction which will effect such equal drives of the two slots.

It will now be clear that this wave guide in which a pure TE_{01} wave has been generated, may be coupled to the resonant cavity 21 of the stacked horn antenna array and a horizontally polarized wave is thus developed.

The circular wave guide 62, as already stated, is chosen such that its diameter is greater than that required to transmit the TE_{01} mode. However, this diameter is smaller than that required for transmission of the next higher mode.

If, however, it is desired to transmit this energy in a larger diameter pipe, and accordingly minimize attenuation, a flared fitting 111 (Figure 1) may be used as a coupler between wave guide section 62 and larger diameter circular wave guides 112 directly coupled in the illustration here to the cavity of the conical horn antenna. As the TE_{21} mode is completely suppressed as described, the energy propagated in the larger diameter section 112 is essentially the TE_{01} mode in pure form.

As this oscillation mode is transmitted with minimum attenuation, it is clear that transmission of high frequency energy over considerable distances as, for example, inter-city communication, may be best accomplished by this arrangement, the wave guide of which may be of the order of six inches in diameter.

As various modifications of the transducer units illustrated and described above may be evident to those skilled in the art, I prefer that the scope of this invention be defined by the appended claims.

I claim:

1. In a high frequency system, a first wave guide conducting high frequency energy, a second circular wave guide, said first wave guide having two branches extending on opposite sides

of said second wave guide, a symmetrical arrangement of slots diametrically opposed in said second circular wave guide, a symmetrical arrangement of slots diametrically opposed in said first wave guide and in juxtaposed relation with said first mentioned slots in said circular wave guide for providing a coupling between said second circular wave guide and said first wave guide, means for driving said slots from the first wave guide in the same time phase with respect to the TE_{01} mode and in the same phase for exciting the TE_{01} mode in said second wave guide.

2. In a high frequency system, a first rectangular wave guide conducting high frequency energy, a second circular wave guide, said first wave guide having two branches extending on opposed sides of said second circular wave guide, a symmetrical arrangement of slots in the walls of said second circular wave guide adjacent to the walls of said first wave guide, a symmetrical arrangement of slots in the walls of said first wave guide adjacent to the walls of said second wave guide, said slots being juxtaposed with respect to each other for coupling said second wave guide to said first wave guide, means for exciting said slots in said first wave guide equally in such phase as to excite the TE_{01} and TE_{21} modes in said second wave guide, and means within the second wave guide for balancing out the TE_{21} mode.

3. In a high frequency system, a first rectangular wave guide conducting high frequency energy, a second circular wave guide, said first wave guide having two branches extending on opposed sides of said second wave guide, a symmetrical arrangement of slots in the walls of said first wave guide adjacent the walls of said second wave guide, a symmetrical arrangement of slots in the walls of said second wave guide adjacent the walls of said first wave guide, said slots in said first wave guide being juxtaposed to the slots in said second wave guide for coupling said second wave guide to said first wave guide, said slots being in diametrically opposed relation with respect to each other, and means for exciting said slots in said first wave guide equally and in such phase as to excite the TE_{01} mode in said second wave guide.

4. In a high frequency system, a first rectangular wave guide conducting high frequency energy, a second circular wave guide, said first wave guide having two branches extending on opposed sides of said second wave guide, a symmetrical arrangement of slots in the walls of said first wave guide adjacent the walls of said second wave guide, a symmetrical arrangement of slots in the walls of said second wave guide adjacent the walls of said first wave guide, said slots being juxtaposed with respect to each other for coupling said second wave guide to said first wave guide, means for driving said slots from the first wave guide in the same time phase with respect to the TE_{01} mode in said second wave guide, and means within the second wave guide for balancing out the TE_{21} mode.

5. In a high frequency system, a rectangular wave guide conducting high frequency energy, a second wave guide, a third wave guide having two branches, said rectangular wave guide being joined to said third wave guide at the junction of the two branches, the branches extending to opposite sides of said second wave guide and slots formed in said two wave guide branches, and said second wave guide in diametrically opposed relation with respect to each other, said slots of said two wave guide branches being juxtaposed to

the corresponding slots of the second wave guide, said slots being symmetrically arranged to receive equal and in phase energy from said rectangular wave guide.

6. In a high frequency system, a rectangular wave guide conducting high frequency energy, a second wave guide, a third wave guide having two branches, said rectangular wave guide being joined to said third wave guide at the junction of the branches, the branches extending to opposite sides of said second wave guide and slots formed in said two wave guide branches, and said second wave guide, said slots of said two wave guide branches being juxtaposed to the corresponding slots of the second wave guide, said slots being symmetrically arranged to receive equal energy from said rectangular wave guide, and a closure for said second wave guide at a critical distance from said slots for balancing out the TE_{21} mode.

7. In a high frequency system, a rectangular wave guide conducting high frequency energy, a second wave guide, a third wave guide having two branches, said rectangular wave guide being joined to the third wave guide at the junction of the two branches, the branches extending to opposite sides of said second wave guide and slots formed in said two wave guide branches and said second wave guide, said slots of said two wave guide branches being juxtaposed to the corresponding slots of the second wave guide, said slots being symmetrically arranged to receive equal energy from said rectangular wave guide, said wave guide branches being closed at their ends at a distance to the slots formed therein substantially equal to one half wave length.

8. In a high frequency system, a rectangular wave guide conducting high frequency energy, a second wave guide, a third wave guide having two branches, said rectangular wave guide being joined to the third wave guide at the junction of the two branches, the branches extending to opposite sides of said second wave guide and slots formed in said two wave guide branches and said second wave guide, said slots of said two wave guide branches being juxtaposed to the corresponding slots of the second wave guide, said slots being symmetrically arranged to receive equal energy from said rectangular wave guide, said wave guide branches being closed at their ends at a distance to the slots formed therein substantially equal to one half wave length.

9. In a high frequency system, a rectangular wave guide conducting high frequency energy, a second wave guide, a third wave guide having two branches, said rectangular wave guide being joined to the third wave guide at the junction of the branches, the branches extending to opposite sides of said second wave guide and slots formed in said two wave guide branches and said second wave guide, said slots of said two wave guide branches being juxtaposed to the corresponding slots of the second wave guide, said slots being symmetrically arranged to receive equal energy from said rectangular wave guide, the cross-sectional dimensions of said wave guide branches being determined by the input impedance of the slots for the TE_{01} mode.

10. In a high frequency system, a rectangular wave guide conducting high frequency energy, a circular wave guide having diametrically opposed slots, and a transducer extending from said rectangular to said circular wave guide for coupling said wave guides, said transducer comprising two diametrically opposite slots juxtaposed to

said slots in said circular wave guide having two way axial symmetry in the circular dimension.

11. In a high frequency system, a rectangular wave guide conducting high frequency energy; a circular wave guide having diametrically opposed slots, and a transducer extending from said rectangular to said circular wave guide for coupling said wave guides, said transducer comprising two diametrically opposite slots juxtaposed to said slots in said circular wave guide having two way axial symmetry in the circular dimension, said circular wave guide being closed at one end at a critical distance from said slots for suppressing the TE₂₁ mode.
